No. 36,923.

Patented May 24, 1904.

UNITED STATES PATENT OFFICE.

LOUIS F. MORLOCK, OF ST. LOUIS, MISSOURI.

DESIGN FOR A MATCH-CASE.

SPECIFICATION forming part of Design No. 36,923, dated May 24, 1904.

Application filed February 15, 1904. Serial No. 193,741. Term of patent 7 years.

To all whom it may concern:

Be it known that I, LOUIS F. MORLOCK, a citizen of the United States, residing at St. Louis, State of Missouri, have invented a new, original, and ornamental Design for a Match-Case.

My design is shown in the accompanying drawings, in which—

Figure 1 is a front elevation of a match-case embodying my design. Fig. 2 is a perspective view showing the side opposite the front. Fig. 3 is a top plan view.

What I claim is—

The ornamental design for a match-case, as shown.

LOUIS F. MORLOCK.
